CIGARETTE LIGHTER

Filed May 8, 1928

UNITED STATES PATENT OFFICE

EDMOND T. PATNAUDE, OF PROVIDENCE, RHODE ISLAND, ASSIGNOR TO CLARK LIGHTER CO. INC., OF NEW YORK, N. Y., A CORPORATION OF MARYLAND

CIGARETTE LIGHTER

Application filed May 8, 1928. Serial No. 276,042.

This invention relates generally to pocket cigar and cigarette lighters.

One of the objects of this invention is the construction of a cigarette lighter employing an improved flint tube construction.

A still further object of this invention is the construction of an improved flint tube having means for feeding the flint as it is worn away without the unsightly projection 10 of the controlling thumb screw.

A still further object of this invention is the construction of pressure controlling means for forcing the flint against the sparking wheel by a construction which is exceedingly simple and cheap to manufacture and assemble.

These and other objects, as will appear from the following disclosure, are secured by means of this invention.

20 This invention resides substantially in the combination, construction, arrangement and relative location of parts all as will more fully appear hereinafter.

Referring to the drawings—

25 Figure 1 is a side elevational view of the device showing the improved flint tube;

Fig. 2 is a vertical cross sectional view of the flint tube;

Fig. 3 is an enlarged view similar to Fig. 30 2 with some parts broken away;

Fig. 4 is a side elevational view of a modified form of construction and Fig. 5 is a vertical cross sectional view of this construction;

Fig. 6 is a perspective view of an element 35 employed in the form shown in Figs. 1, 2 and 3;

Figs. 7 and 8 are vertical cross sectional views in two stages of construction of a modified knurled thumb member employed on 40 the end of the flint tube;

Fig. 9 is an enlarged cross sectional view of the modified form using the knurled thumb member of Figs. 7 and 8.

Fig. 10 is a side elevational view of the flint 45 tube used in this modification;

Fig. 11 is a similar view showing the knurled thumb member applied to the flint tube;

Fig. 12 shows a modified form of the de- 50 vice; and

Fig. 13 is a cross sectional view on the line 13—13 of Fig. 12.

In the usual forms of cigarette lighters now found on the market the flint tube comprises a hollow tubular member within which the flint or sparking material moves. A spring within this tube presses the sparking member against the sparking wheel and a long threaded screw extends into the flint tube which is internally threaded and presses against the 55 spring. When the new flint or sparking element is placed within the tube the threaded screw projects a considerable distance from the end of the flint tube and as a result is unsightly as well as cumbersome. As the flint or 60 sparking material wears away the thumb screw is moved into the tube causing the spring to advance the flint so that when the flint is substantially all gone the thumb screw is entirely within the flint tube. It is apparent then that in the two extremes the 65 threaded screw is either projecting from the flint tube for a considerable distance or else is all the way in and at various positions between these limits depending upon the length 70 of the flint. It is the purpose of this invention to provide a construction whereby the thumb screw which adjusts the pressure on the flint is at all times close up to the end of the flint tube regardless of the length of the 75 flint or sparking material. This construction results in a pocket lighter which is neat in 80 appearance.

Referring to the drawings, the lighter is shown comprising a fluid container 1 having 85 a threaded plug 2 in an opening in the container through which the container may be filled. The upper end of the container is provided with a vertical post 3 rigidly secured thereto through which and in which is mounted the hollow flint tube 4 provided with a recessed cap member 7 which protects the steel 90 sparking wheel. Also mounted in the top of the container 1 is a short vertical rotatable shaft 5 having a thumb wheel 6 by means of which the shaft may be rotated by the user's thumb. The upper end of the shaft 5 is provided with the milled steel wheel which lies within the recess in the cap member 7 as 95 is well known in the art.

In Fig. 2 the flint tube 4, which is shown in cross section, houses the flint or sparking material 8. The bore extending through the flint tube extends completely through so that the flint 8 can contact with the steel wheel within the cap 7. A spring 9 presses against the flint 8 and a threaded plug 11 having the integral extension 12 moves back and forth when it is rotated within the flint tube by reason of the threads on the internal surface of the flint tube. The extension 12 is square or rectangular in cross section. The length of the threads and the length of the extension 12 are such that the plug 11 cannot be advanced so as to get out of control of the member 14. This plug member 14 fits over the extension 12 at one end and at the other end extends through a cap 13 which is secured to the flint tube by the threads on the external surface thereof.

The plugged member 14 is provided with a knurled head 15 by means of which it may be rotated. It will be apparent that as the members 14 and 15 are rotated they cause the plug 11 to rotate and thus advance along the flint tube forcing the flint against the spark wheel through the agency of the spring. It will be apparent that by means of this construction the knurled member 15 always lies in the same position with respect to the flint tube and does not extend therethrough at varying distances as in the usual form of device.

In the modified construction of Figs. 4 and 5 a plugged member 30 similar to the member 14 is employed which is provided with a pin 34 extending transversely of the plugged end. The plug 31 is provided with an integral extension 32 which in this case is slotted at 33 so as to enclose the pin 34. By means of this construction the plugged member 30 and plug 31 form an integral unit, the elements of which cannot be separated and thus lost.

In the modified construction of Figs. 7 to 11 the flint tube 4 is provided with a boss 42 and is longitudinally slotted a short distance as at 43. A member 40 is constructed in the form of a cap having a bore at one end and a conical edge at the other. This edge is folded over, as shown at 41, to provide an internal boss on the end thereof. The plugged member 14 in this case is riveted to the cap 40, as shown. The cap 40 is of such size with respect to the flint tube that it can, under suitable pressure, be forced over the end thereof which is resilient by reason of the slot 43. The bosses 41 and 42 cooperate to hold the cap 40 on the end of the flint tube. As before, a plug of the forms 11 or 31 may be used.

In the form of the device shown in Figs. 12 and 13 a cap member 50 similar to the cap member 13 is constructed so as to removably engage the threaded end of the flint tube. Mounted in the cap member 50 for rotation is a short rod member 51 provided with a thumb nut 52 so that it may be rotated in

the cap member. The member 51 is provided with a recess or bore 53 which is off center, as is clear from Fig. 13. A threaded plug 54 adapted to engage the internally threaded surface of the flint tube is provided having a projection 55 formed thereon off center so that when the members 51 and 54 are in alignment the projection 55 will seat in the recess 53. The result is a device operated on the principle of a crank so that as the thumb nut 52 is rotated the plug 54 is rotated through the crank action of the members 51 and 55. It is apparent that this form of construction adapts itself to ease and rapidity of manufacture and represents a rugged form of the device.

It will be at once apparent that I have devised a new and novel form of flint tube construction for pocket cigarette lighters which employs certain principles of construction. I am well aware that some changes in the details of construction and relative arrangement of parts may occur to those skilled in the art and I do not, therefore, desire to be limited to the exact form of device disclosed by me for purposes of illustration but rather to the scope of the invention as it is defined in the appended claims.

What I seek to secure by United States Letters Patent is:

1. In a construction for a cigarette lighter, the combination with a flint tube comprising a hollow member longitudinally slotted at one end and having a boss thereon, of a cap member having a boss on one end thereof for engaging the boss on the flint tube and a slotted member secured to the cap so as to extend internally of the flint tube when the cap is applied thereto.

2. In a cigarette lighter, the combination with a container, of a flint tube mounted thereon and having threads internally and externally thereof, a threaded plug adapted to engage the internal threads and having an integral extension, a bifurcated member engaging said integral extension, a threaded cap adapted to be threaded onto the end of said flint tube and present a shoulder to prevent the withdrawal of said bifurcated member, and means extending through said cap and joining said bifurcated member with a thumb wheel so that rotation of the thumb wheel turns said bifurcated member and causes the threaded plug to move backwards and forwards as a function of the direction of rotation of said thumb wheel.

3. In a pocket cigarette lighter, the combination with a container of a hollow flint tube internally and externally threaded for a predetermined distance, a flint slidably mounted within the tube, a spring pressed against the flint and a threaded plug engaging the spring at its free end and moving on the internal threads aforementioned, an integral extension on said plug and a bifurcated

- member fixed longitudinally with respect to the flint tube and grasping said integral extension, a threaded cap threaded onto said flint tube externally thereof and having there-
5 in a hole through which an extension of said bifurcated member may be attached to a thumb wheel for purposes of rotating said plug by the engagement with said extension to vary the pressure on the spring.
- 10 4. In a pocket cigarette lighter, the combination with a container, of a flint tube mounted thereon, said tube being internally and externally threaded, a threaded plug having an integral extension and adapted to move longitudinally of the tube on the internal threads, a bifurcated member extending into the tube and engaging said extension, a cap having a central hole therein attached to the flint tube through which the bifurcated member extends for holding it within the tube, and means external of the flint tube and secured to said bifurcated member whereby rotation of said means is adapted to similarly actuate said plug.
- 15 5. In a pocket cigarette lighter, the combination with a container of a flint tube having internally and externally threaded portions, threaded means within the flint tube adapted to engage the internally threaded portion, means extending into the flint tube for rotating said threaded means, and further threaded means secured to the flint tube at its externally threaded portion for preventing the withdrawal of the means extending into the flint tube.
- 20 6. In a flint advancing mechanism for cigarette lighters, the combination with a lighter body and a flint tube mounted thereon, of a flint located in said tube, means for imparting a spring pressure to said flint, including a threaded plug having an integral extension thereon, unthreaded means freely rotatable within said tube and engaging said extension for increasing the tension of said spring, and means disposed at the end of said tube for preventing the withdrawal of said unthreaded means.
- 25 7. In a flint advancing mechanism for cigarette lighters, the combination with a lighter body and a flint tube mounted thereon, of a flint located in said tube, means for imparting a spring pressure to said flint including a threaded plug having an integral extension thereon, unthreaded means freely rotatable within said tube and engaging said extension for increasing the tension of said spring, and threaded means disposed at the end of said tube for preventing the withdrawal of said unthreaded means.
- 30 8. In a flint advancing mechanism for cigarette lighters, the combination with a lighter body and a flint tube mounted thereon, of a flint located in one end of said tube, of a member rotatably mounted in the opposite end of said tube, a screw plug in threaded en-
gagement with the interior of said tube, an integral extension mounted on said plug, a resilient member interposed between the plug and the flint, bifurcated means for engaging said extension and moving said plug on rotation of said member, and means threaded externally onto said tube for normally preventing removal of the bifurcated member from said tube.
- 35 9. In a flint advancing mechanism for a cigarette lighter, the combination with a lighter body and a flint tube mounted thereon, of a flint located in said tube, means for imparting a spring pressure to said flint, including a threaded plug having an off-centered cylindrical extension thereon, unthreaded means freely rotatable within said tube having an off-centered recess therein in which said integral extension is adapted to work, for increasing the tension of said spring, and means disposed at the end of said tube for preventing the withdrawal of said unthreaded means.
- 40 10. In a flint advancing mechanism for a cigarette lighter, the combination with a lighter body and a flint tube mounted thereon, of a flint located in said tube, means for imparting a spring pressure to said flint including a plug member having an off-centered integral extension thereon, and means movable within said tube having an off-centered recess therein in which the integral extension may seat for cooperation therewith to increase the compression of said spring.
- 45 11. In a flint advancing mechanism for a cigarette lighter, the combination with a lighter body and a flint tube mounted thereon, of a flint located in said tube, a resilient member disposed within said tube against said flint, means disposed within said tube for compressing said resilient member to bring pressure to bear on said flint, said means including a plug member having an eccentrically disposed extension thereon, and further means extending into said flint tube and adapted for engagement and cooperation with said extension.
- 50 12. In a flint advancing mechanism for a cigarette lighter, the combination with a lighter body and a flint tube mounted thereon, comprising a hollow member having a boss thereon, of a flint located in said tube, a resilient member disposed within said tube against said flint, means disposed within said tube for compressing said resilient member to bring pressure to bear on said flint, said means including a plug member having an extension thereon, a cap member having a boss on one end thereof for engaging with the boss on the flint tube, and further means secured to said cap and extending internally of the flint tube when the cap is applied thereto for engaging with the said extension.
- 55 13. In a construction for a cigarette lighter, the combination with a flint tube comprising

a hollow member having a boss on the outer surface of the end thereof and means disposed in said flint tube for imparting pressure to a flint, of a cap member having a boss on the inner surface at one end thereof for engagement with the boss on the flint tube, and a member secured to the cap so as to extend internally of the flint tube when the cap is applied thereto for engagement with and actuation of the means for imparting pressure to the flint.

In testimony whereof I have hereunto set my hand on this 26th day of April, A. D. 1928.

EDMOND T. PATNAUDE.
